UNITED STATES PATENT OFFICE.

CYRUS E. BENNETT, OF BUFFALO, NEW YORK.

GARMENT-POCKET.

1,387,342.

Specification of Letters Patent. Patented Aug. 9, 1921.

Application filed March 10, 1920. Serial No. 364,667.

To all whom it may concern:

Be it known that I, CYRUS E. BENNETT, a citizen of the United States, residing at Buffalo, in the county of Erie and State of New York, have invented certain new and useful Improvements in Garment-Pockets, of which the following is a specification.

My invention relates to a garment pocket, and more particularly to a pocket having means to lock it against surreptitious entrance so as to guard against theft of the contents.

My invention has for its object the provision of a simple and effective device of this character which may be applied to any form of pocket and be easily manipulated by the wearer of the garment equipped with the pocket so improved.

The invention consists in the novel features of construction and in the arrangement and combination of parts to be hereinafter described and more particularly pointed out in the subjoined claims.

In the drawings:

Figure 1 is a sectional elevation of a garment showing a portion thereof broken away to illustrate my improved pocket, the pocket being shown locked against entrance thereto.

Fig. 2 is a cross section through the pocket taken on or about line 2—2, Fig. 1, the pocket being shown extended to permit entrance thereto.

In the drawing, A represents an outer garment, in this particular instance, a portion of a pair of trousers having a side pocket formed with an entrance along the outer seam of one of the trouser legs. B is the conventional form of trouser pocket, opening at a side seam. At intervals around the pocket I provide openings C, which are preferably in the form of eyelets fastened into the material from which the pocket is constructed, but these openings may be otherwise formed if desired.

Passing through the openings in a zigzag manner, as clearly shown in Fig. 2, is a non-elastic draw or shirring string or band D, with the ends thereof suitably connected so that it is in the form of an endless band after it is passed back and forth through the openings in the pocket. This string or band is therefore arranged to have parts thereof lie alternately outside and inside of the pocket, as clearly shown in Fig. 2, and when the pocket is extended so that entrance may

be had thereto, there is practically little or no looseness in the string or band, and access may be conveniently had to the pocket without the string or band interfering with the entrance of matter into the pocket, or the removal of the same therefrom.

Arranged at the opening of the pocket, preferably at a high point, is a retainer E, which in the drawing is shown in the form of a spring hook sewed to the pocket directly inside of the opening thereof, and when it is desired to close the pocket inside of the entrance opening or, in other words, "lock" the pocket, as it may be termed, it is simply necessary to grip the draw or shirring string or band at F, Fig. 2, and pull on the same so as to provide a loose part or loop, which part or loop may be engaged with the retainer or spring hook, the space between the free end of the hook and the body of the retainer being preferably a trifle smaller than the diameter of the string or band so that it will be necessary to exert force to slip the string or band over the hook or to remove the same therefrom. When this draw or shirring string or band is pulled upon and engaged with the retainer E, the pocket will be shirred or drawn together in parallel runnings between its ends and thus prevent entrance to the pocket, thereby assuring safety to its contents.

Having thus described my invention, what I claim is:

1. In combination with a garment, a pocket in said garment having a series of openings, non-elastic shirring means passed through said openings and adapted to shirr the material of the pocket to lock the pocket against entrance, and means within said pocket to hold the shirring means in locking position.

2. In combination with a garment, a pocket in said garment having a series of spaced openings around the same, a shirring string passed through said openings to shirr the pocket and lock the same against entrance, and means within said pocket to retain the freely drawn portion of the shirring string against movement so as to prevent the extending or opening of the pocket.

3. In combination with a garment, a pocket within said garment, a shirring string applied to said pocket and adapted to be drawn upon to shirr said pocket between its ends, and a retaining device within said pocket conveniently accessible through the

opening of said pocket and adapted to be engaged by the drawn-out portion of said shirring string to hold the string against unloosening.

5. In combination with a garment, a pocket in said garment having a series of openings around the same, an endless non-elastic shirring string passed through said

openings and adapted to be drawn upon to shirr the pocket in the regions of said openings, and a retainer hook in the pocket above said openings onto which the drawn out portion of the shirring string is to be hooked when the pocket is shirred.

In testimony whereof I affix my signature. 15

CYRUS E. BENNETT.
